UNITED STATES PATENT OFFICE

NICHOLAS J. CONRAD, OF WILMETTE, ILLINOIS, ASSIGNOR TO SCHWEITZER & CONRAD, OF CHICAGO, ILLINOIS, A CORPORATION OF ILLINOIS

FUSE DEVICE AND THE LIKE

Application filed April 11, 1923. Serial No. 631,263.

My invention relates to fuse devices and the like and is concerned more particularly with fuse devices of the liquid containing type.

5 The chief object of my invention is to simplify and improve the construction and assembly thereof.

Another object is the provision of an improved process or method of sealing the ends 10 of the tube or other enclosing member in the ferrule or terminals employed.

Another object is the provision of an improved substance for sealing the ends of the tube and the vent cap in the ferrules.

15 A further object is the provision of an improved clip and mounting for the fuse and;

A still further object is the provision of an improved process or method of refilling or renewing the fuse.

20 In order to acquaint those skilled in the art with the manner of constructing and practicing my invention I shall now describe, in connection with the accompanying drawings certain specific embodiments of the invention.

In the drawings:

Fig. 1 is a longitudinal section of a fuse embodying my invention;

Fig. 2 is a fragmentary longitudinal section of the same after the fuse has blown;

Fig. 3 is a transverse section taken on the line 3—3 of Figure 1;

Fig. 4 is a longitudinal section of the upper arcing terminals taken on the line 4—4 of Figure 1;

Fig. 5 is a top plan view of the lower internal terminal showing the manner of attaching the lower end of the internal conducting cable or strand thereto.

40 Fig. 6 is a longitudinal section of the same.

Fig. 7 is a longitudinal section of a fuse of modified form.

Fig. 8 is a fragmentary longitudinal section of the same after the fuse has blown.

45 Fig. 9 is a top plan view of the fuse shown in Figures 7 and 8 with the vent cap removed.

Fig. 10 is a transverse section taken on the line 10—10 of Fig. 7.

50 Fig. 11 is a longitudinal section through

the upper arcing terminal taken on the line 11—11 of Fig. 7.

Fig. 12 is a side elevational view partially in section of the lower internal terminal.

Figs. 13 and 14 are longitudinal sections 55 more or less diagrammatic showing the manner of sealing the ends of the tube in the ferrules.

Fig. 15 is a sectional view showing the step of preparing the sealing substance.

Fig. 16 shows the step of drying and heating the assembled fuse in refilling or renewing the same.

Fig. 17 shows the step of preparing the fuse liquid preparatory to introducing the 65 same into the fuse;

Fig. 18 is a side elevational view of the fuse mounting;

Fig. 19 is an enlarged front elevational view of one of the fuse clips;

Fig. 20 is a top plan view of the same, and

Fig. 21 is an enlarged fragmentary perspective view of said clip, taken from one side thereof.

The body of the fuse illustrated in Figures 75 1, 2, 3, 4, 5 and 6 is formed of a sleeve or tube 1 of insulating material. While the particular tube selected for illustration is cylindrical in form and is made of glass, it is to be understood that the particular formation may be 80 varied and the body 1 may be formed of fibre impregnated with "bakelite" or any other suitable or desired insulating material. Upon the ends of the sleeve or tube 1 are secured the metal ferrules 2 and 3 which form 85 terminals for the conducting parts of the fuse contained within the sleeve 1.

The lower end or bottom of the lower ferrule 3 is closed as shown at 4. A boss 5 projects upwardly from the center of the closed 90 end or bottom 4 and is bored and internally threaded to receive the threaded end 6 of a terminal member 7 secured upon the lower end of a flexible stranded conductor or cable 8 which extends through the body of the fuse 95 and is connected at its upper end to the upper arcing terminals 9 and 10.

The terminal member 7 and the upper arcing terminals 9 and 10 are formed of metallic sleeves or tubes. The lower end of the me- 100

tallic sleeve or tube forming the terminal member 7 is threaded as shown at 6 to be secured into the internally threaded boss 5 of the ferrule 3 closing the bottom or lower end 5 of the tube 1. The lower end of the stranded conductor 8 is inserted into the open upper end of this terminal sleeve 7 and union between the sleeve 7 and strand 8 is then produced by deforming the upper end of the 10 sleeve as by crushing or pressing it inwardly into substantially the shape or configuration shown to compress the fibres of the stranded conductor and firmly and securely grip them in the terminal sleeve. The formation of 15 the upper end of the sleeve into substantially the shape shown permits engagement by a wrench or other suitable tool for the purpose of threading the lower end of the sleeve into the boss 5. In addition I find that the union 20 between the terminal member 7 and conductor 8 thereby formed provides an efficient, simple and inexpensive electrical and mechanical connection between the cable and the terminal.

25 The lower end of a coil tension spring 11 connected between the terminals 7 and 10, is bent diametrically with respect to the convolutions of the spring and is clamped between one of the upper flat faces of the terminal member 7 and a clip member 12 secured thereto as by means of a suitable screw 13 threaded through the clip 12 and into a threaded opening formed through the upper end of the terminal 7 in which the conductor 30 8 is secured. The member 7 therefore in addition to electrically and mechanically connecting the lower ends of the conductor 8 to the ferrule 3 forms connection for the lower end of the operating spring 11. While the 35 terminal 7 and clip 12 may both be grooved if so desired I find that a groove 14 across the inner face of the clip 12 provides sufficient retention for the lower end of the spring 11.

The upper end of the conductor or cable 8 40 is secured in a connecting member 15 which like the terminal 7 is formed of a metallic sleeve into which the conductor is inserted and the sleeve 15 and conductor then connected or united by crushing or pressing the 45 sleeve to distort the same and compress the fibres of the conductor and firmly and securely grip them in the sleeve. The upper end of the spring 11 is bent diametrically like the lower end and is secured between the connecting sleeve 15 and the lower arcing terminal 10, the sleeve 15 and terminal 10 being 50 clamped together by a suitable screw 16 and the inner face of the terminal 10 being provided with a groove 17 in which the upper end 55 of the spring 11 is secured.

The arcing terminals 9 and 10 are formed of metallic sleeves into the adjacent ends of which the opposite ends of a fuse link 18 and strain wire 19 are inserted and opposite sides 60 65 of the sleeves forming these terminals then

crushed or pressed into substantially the formation shown in Figure 4 to securely grip them therein. A simple and effective mechanical and electrical connection is thereby provided between the fuse and strain links 70 18 and 19 and the arcing terminals 9 and 10. The adjacent ends of the terminals 9 and 10 fit snugly and the fuse link 18 and strain wire 19 connected therebetween are confined in a relatively wide narrow passage 20 formed in a nonconducting plug 21, which is preferably made of cork. The fuse link or wire 18 being of rather soft metal is not adapted to withstand the strain imposed by the tension of the spring 11 and the wire 19 is therefore 80 employed to withstand such strain and normally hold the parts in set position. The wire 19 forms the mechanical connection and the fuse link is rated to break the circuit at the desired point.

85 A liquid directing or spraying member 22 is mounted upon the lower arcing terminal 10 by means of a suitable screw 23 the head of which screw is countersunk into the member 22 as shown. This liquid directing or spraying member which is preferably made of lava, tends to direct or squirt liquid upon the place where the arc is drawn when the fuse blows. The liquid director 22 is in fact a plunger fitting more or less closely in the body of the fuse and having a central opening the lower end of which is preferably tapered or flared outwardly to the lower end of the director as shown.

90 The upper ferrule 2 is provided with an interior flange 25. This interior flange 25 forms an internal annular shoulder shown at 26 for the reception of a vent cap 27 provided for closing off the upper ferrule 2 and a second annular shoulder shown at 28 for supporting 95 a terminal supporting member 29. The terminal supporting member 29 which is of general S-shaped formation and which is more or less resilient in order to secure good contact with the sidewalls 25' of the ferrule 2, includes a substantially diametrically extending intermediate portion 30 to which the upper end of the upper arcing terminal 9 is adapted to be secured as by means of a screw 32 which extends through an opening in the intermediate portion 30 of the supporting member 29 and through a registering opening 34 in the upper end of the terminal 9 and engages at its opposite end a suitable nut 35.

100 To facilitate setting of the fuse the terminal 9 is provided with an aperture 38 just below the aperture 34. In setting, the interior working parts are all properly connected between the lower terminal 7 and the upper arcing terminals. The lower end of the terminal member 7 is then threaded into the boss 5 projecting from the ferrule 3 and a tool having a hooked end is inserted into the tube and engaged in the aperture 38. The terminal 9 is then drawn upwardly through the 105 110 115 120 125 130

tube 1 against the tension of the spring 11 until the aperture 34 registers with the screw 32 in the intermediate portion 30 of the supporting member 29. Aperture 34 is hooked upon screw 32 which is previously threaded into cross member 30. A nut 35 is then threaded upon screw 32 and it clamps the terminal 9 to the cross piece 30.

The sleeve or tube 1 is normally substantially filled with an arc extinguishing liquid which is introduced preferably through the open end of the ferrule 2 in a manner which will be hereinafter more fully described and the vent cap 27 quickly secured in place. The arc extinguishing liquid employed is preferably a derivative of a suitable hydrocarbon. It may be any one of the liquids disclosed in Patent No. 1,319,907, dated October 28, 1919, or any preferred arc extinguishing liquid.

It is believed that the operation of the fuse will be apparent from the foregoing description. The non-conducting plug 21 conserves and localizes the heat generated in the fusible wire 18 and when this wire is melted or fused, the strain or tension wire 19 is subjected to a heavy current. It is immediately fused and the spring 11 draws the lower arcing terminal 10 down from the upper arcing terminal 9. The plunger or director 22 moving downwardly with the terminal 10 projects a stream of the arc extinguishing liquid 40 upon the space where the arc tends to form.

Severe blowing tends to generate an excessive pressure in the container. The cap 27 provides relief by blowing off. This cap is sealed in place by a viscous non-hardening cement which provides a good seal and which provides a fairly uniform and definite mechanical bond. This bond tends to rupture at a fairly definite pressure, thereby preventing damage to the other parts of the container.

In the form shown in Figs. 7 to 12 inclusive the lower terminal member 50 comprises a pin or post the lower end of which is threaded as shown at 51 to be secured into the internally threaded boss 52 projecting upwardly from the center of the ferrule 53 closing off the lower end of the body 54 of the fuse. The upper end of the terminal 50 which is bored out as shown at 55 is inserted through a block 56, the threads 51 being preferably formed sufficiently larger than the inserted end to retain the member 50 against displacement through the block 56 in one direction.

The lower end of the stranded conductor 57 is inserted in the upper bored out end of the terminal 50 and union between the strand and said member is then produced by crushing or pressing the wall of said member inwardly at opposite points to compress the fibres of the stranded conductor and firmly and securely grip them in the terminal member. As before a simple, efficient and inexpensive mechanical and electrical connection is thereby provided.

The flat faces formed in the terminal member

50 permit engagement by a suitable tool for screwing the lower end of the terminal into the boss 52 and at the same time the swedging or crushing out of the upper end of the terminal forms retention shoulders for preventing displacement of the terminal 50 through block 56 in the opposite direction.

The screw 58 threaded through the block or collar 56 and into a threaded opening in the intermediate portion of the terminal 50 provides an additional securing means between the terminal 50 and collar 56 and prevents relative rotation therebetween. In addition the head of the screw 58 is splayed or flattened at one side for cooperation with the spring 59 one of the lower convolutions of which extends between the head of the screw 58 and a pin 60 mounted in and projecting from the collar or block 56. A pin 61 projecting from the opposite side of the block 56 engages between two of the lower convolutions of the spring 59 and the spring is thereby connected to the block 56 in a simple and effective manner. One of the pins 61 is preferably positioned below the other as shown to permit threading of the lower convolution of the spring into cooperation therewith.

The upper end of the conductor 57 is secured in a movable terminal 65. The terminal 65 comprises a stem or post the lower end of which is bored out as shown at 66 to receive the conductor 57 which is inserted therein. The terminal 65 is then crushed or pressed inwardly at opposite points into substantially the shape shown in the drawings thereby firmly and securely gripping the conductor in the bored out end of the terminal and effecting a simple, efficient and inexpensive electrical and mechanical connection therebetween. The upwardly extending shank 67 of the terminal member 65 projects through a collar or block 68 mounted thereupon and secured against longitudinal movement and rotation relative thereto. Like the lower block 56 the block 68 is provided with a pair of off-set projecting pins 69 and 70 into cooperation with which the upper convolutions of the spring 59 are threaded and thereby secured. A screw 71 provides an additional securing means between the block 68 and terminal 65 and additional retention for the upper end of the spring 59.

The upper ferrule is provided with an internal flange 76 which flange 76 is formed with an annular shoulder 77 for the reception of the vent cap, 78, a second annular shoulder 79 and an outwardly flared or tapered surface 80. An annular ring 81 mounted in the ferrule 75 upon the shoulder 79, supports a non-conducting washer 82 through which the upwardly extending shank 67 of the arcing terminal 65 projects. The terminal 65 is held in place by a strain or tension wire 83 which passes through the

shank 67 and is secured at each end under the heads of suitable screws 84 mounted at diametrically opposite points in the flared or tapered surface 80. The top or upper end 5 of the shank 67 is provided with a removable screw 85 under which the intermediate portion of a fuse link 86 is secured. The opposite ends of the link 86 are mechanically and electrically connected to the ferrule by screws 10 87 mounted in the surface 80 at diametrically opposite points. The liquid directing or spraying member 88 is mounted upon the shank 67 of the terminal 65 by means of three screws 89 the heads of which are countersunk as shown at 90.

15 The upper terminal 65 is guided by a plurality of fingers 92 formed of wire and secured to the terminal 65. These fingers tend to prevent vibration of the movable system 20 when the fuse is in operative condition. To obtain a simple, effective and inexpensive scheme of forming these fingers and securing them in place, I have devised the arrangement shown. One of the pairs of fingers 92 25 is formed of a single length of wire which passes through an opening 93 in the shank of the terminal 65 and is then bent around the periphery of the shank 67, 90 degrees in the particular embodiment shown, and passed 30 through an opening 94 at substantially right angles or normal to the opening 93. The other pair of fingers is formed of a similar length of wire passed through an opening 95, bent around the periphery of the shank 67, 35 90 degrees and then passed through an opening 96 substantially normal to the opening 95. This provides a simple, inexpensive and efficient scheme for securing the wires, the projecting ends of which cooperate with the 40 inside of the tube to guide the movable working parts of the fuse, and also to damp any vibrations of the spring and connected parts. Otherwise such vibrations might impose destructive stresses upon the wire 83.

45 As in the embodiment illustrated in Figures 1 to 6 inclusive, when the fuse link 86 is melted or fused, the tension wire 83 is subjected to a heavy current and to the heat generated by the fusing of the link 86. It is 50 fused at once and the spring 59 draws the plunger downwardly, projecting a stream of arc extinguishing liquid 98 upon the space where the arc tends to form.

55 The difficulty of properly sealing the terminal ferrules upon the opposite ends of the tube has presented a considerable practical problem heretofore in the art.

To overcome this difficulty I have devised an improved process or method of sealing the 60 ends of the tube or enclosing member in the ferrules or terminals employed. In addition I have discovered a substance which is better adapted or suited for this purpose than anything heretofore used.

65 According to this phase of my invention the

upper ferrule for example the ferrule 2 of the embodiment shown in Fig. 1 is arranged upon a sealing base 100 which sealing base projects upwardly from a suitable heater 101 as shown in Fig. 13. A sleeve 102 preferably surrounds the sealing base 100 and the ferrule 2 arranged thereupon, the sleeve 102 being preferably provided with a tapered or inclined upper edge which flares out from the upper edge of the ferrule 2 for a purpose which will be made apparent as this description proceeds. The glass tube or sleeve 1 of the fuse which is first washed and dried in a vacuum oven, is then inserted into the ferrule 2 with its lower edge resting upon the tapered shoulder 103 therein.

70 A closure piece 104 is then arranged over the upper end of the tube 1 to close off the same. The closure element 104 is provided with a suitable opening through which a suitable vacuum pump 105 is connected with the interior of the tube 1 by means of a tube 106 and connection 107. The closure member 104 is made of or faced with such material as soft rubber, and so formed that it will effectively seal the upper end of the tube 1. The lower end of the ferrule 2 is sealed by cooperation with a suitable seat 109 about the sealing base 100.

75 The ferrule 2 and tube 1 are heated by the heater 101 and the substance employed for sealing the tube in the ferrule is heated to the desired point in a suitable vessel 115 as shown in Fig. 15. This substance is then deposited, as with a suitable knife 116 about the upper edge of the annular space 110 between the tube and ferrule as shown at 111, the upper tapered edge of the sleeve 102 holding sufficient quantity of the material to properly seal the tube in place. The pump 105 is then 80 operated to evacuate the tube 1. The vacuum thus created in the tube 1 acts around the lower edge of the tube resting upon the tapered surface 103 and up through the space 100 100 and draws the sealing substance 111 deposited about the upper edge thereof down and distributes the same uniformly through the space 110. The tapering of the surface 103 provides minimum engagement between the end of the tube and the ferrule and at the same time tends to properly center the tube in the ferrule. Where the tube 1 is of glass as in the embodiments shown the attendant has full vision of the space 110 from 105 the inside and is therefore apprised when the substance 111 is down to the lower end of the tube and distributed uniformly through the space 110.

110 I find that this method quickly, completely and uniformly distributes the sealing substance through the space 110 and that it leaves no pockets, passages or interstices through which leakage is possible.

115 Further difficulty has been encountered heretofore with the substances employed for 120 125

sealing the tube in the ferrule. A substance that becomes hard and brittle will not allow for the different coefficients of expansions of the glass tube and metal ferrule. They are readily cracked and openings and interstices 5 into the tube are gradually formed. This permits leakage and materially increases the rate of evaporation of the arc extinguishing liquid within the tube. Furthermore, the substance should be one that will not be attacked on one 10 hand by the arc extinguishing liquid within the fuse or be permeable to the passage of the liquid therethrough on the other hand.

To overcome these defects I have made a 15 number of experiments to find a substance which is suited for this purpose and find that a suitably treated fusible phenol condensate such as is commonly sold under the trade name of "bakelite" cement, or other substance having similar characteristics is better adapt- 20 ed for this purpose than anything used heretofore. It provides the desired union between the tube and ferrule. It is in the nature of a non-drying cement which will not harden or become brittle. It is yieldable and will not 25 crack. It allows for the different coefficients of expansion of the glass tube and metal ferrules and will not be attacked by the arc extinguishing liquid and is not permeable to the 30 passage of the liquid therethrough.

After the ferrule 2 has been sealed upon the tube or sleeve 1, said tube or sleeve is then provided with the ferrule 3. The ferrule 3 is loosely slipped over the end of the tube 35 or sleeve 1 and the ferrule 3 is then set upon the block 100'. This block is warmed by heater 101 upon which it rests. A split two piece collar 102' having a flaring or funnel shaped upper end is then secured upon the outside of ferrule 3 with a shoulder 108 resting upon the top edge of ferrule 3 so as to provide a filling funnel or trough above the ferrule 3. The upper end of the glass tube or sleeve 1 which bears the ferrule 2 cemented 40 in place, is connected to suction by the valve plug and gasket 104 resting upon the open end of said sleeve 2. The cementitious material is then drawn down into the space between the sleeve 1 and the inside surface of 45 the ferrule 3, in the same manner as heretofore described. The split two-piece collar 102' is prevented from displacement by the overhanging shoulder 108. Obviously, if desired, a solid collar like the collar 102 shown 50 in Fig. 13 may be employed.

Another difficulty has been in renewing or refilling blown fuses. Unless all of the enclosed parts are chemically clean and dry I find that a corrosive action is set up between 55 the liquid and the fuse elements and the metal parts. This impairs the life and functioning of the fuse.

To overcome this difficulty my present invention embraces an improved method of renewing or refilling the fuse. According to

this phrase of my invention the blown fuse upon being first carefully inspected is taken down, that is, the interior working parts, (spring, cable, terminals, liquid director, etc.) are all removed. The glass tube is then 70 washed, thoroughly cleaned, and tested under air pressure to disclose any cracks or weak spots. The spring, cable and terminals are dipped in acid, washed in a neutral bath and dried in a drying oven and the now thoroughly clean tube spring, cable, liquid director, terminals, etc. are reassembled with a new fuse link or wire of the desired capacity. 75

The assembled fuse 120 is then placed in a vacuum oven 121 and gently heated. At the 80 same time the fuse liquid, preferably a derivative of a suitable hydrocarbon, as already pointed out, is brought to the desired temperature, preferably about 50° C. in an electrically heated retort 122 sealed by a cover 85 123. The retort 122 is provided with vent 124. The vent 124 is provided with a calcium chloride and charcoal or other suitable filter 125 which absorbs all moisture and impurities from the entering air. A suitable thermometer 126 may be arranged through the cover 123 and down into the retort 122 to apprise the attendant when the desired temperature is reached. 90

When the temperature of the fuse liquid 95 reaches the desired point and the assembled fuse is thoroughly dried and heated to the desired point, the hot tube is removed from the vacuum oven and filled with the chemically pure and hot fuse liquid as by way of a 100 tube 128. The vent cap 27 or 78 as the case may be with an application of the non-drying cement 111 provided for sealing the ends of the tube in the ferrules, about its upwardly flared flange 132 is then quickly 105 pressed into place and the fuse hermetically sealed. The center of the vent cap is preferably bulged slightly to permit proper springing of the cap into place. The hermetically sealed fuse is then placed in an oven for a 110 heat test to disclose leaks, taken out and subjected to a gas flame test, the presence of the slightest trace of fuse liquid around the joints being indicated by the color of the flame. The fuse is then buffed and cleaned and subjected to an electrical test after which it is 115 ready for use.

The fuse mounting shown in Figs. 18, 19 and 20 comprises a pair of post or supporting insulators 135 suitably mounted at their lower 120 ends upon a base 136. Terminal members 137 mounted upon the upper ends of the insulators 135 carry socket members 138 in which the line conductors are adapted to be secured. 125

Spring contact or fuse clips 139 are mounted upon the terminal members 137. Each of the clips 139 is formed of a metallic strip bent to provide a suitable base, apertured as at 140 for mechanical and electrical connection 130

with the terminals 137 as by means of suitable screws 141. The strip is bent upwardly at the opposite ends of the intermediate base portion 142 substantially normal to said base portion and the opposite upper ends 143 of the strip are curved downwardly to embrace the metallic terminals or ferrules 144 of the fuse 145 which is adapted for insertion therein.

Wire bails 146 are provided for clamping the ferrules 144 in the respective clips 139 and securely holding the same against displacement. The opposite ends of these bails are bent inwardly into apertures in the upwardly extending sides 147 of the clip. These sides 147 normally flare outwardly as shown in dotted lines in Fig. 19 thus permitting easy insertion and withdrawal of the fuse. The downturned ends of the clips 139 are recessed as shown at 190 to permit convenient engagements of a suitable tool with the screws 141. When the fuse is inserted into place the bails 146 are swung up about the ends of the fuse into the positions shown, the sides 147 of the clip being pressed or sprung in to permit the bails to be swung over and embrace the same. The bail is relatively heavy as compared with the thickness of the spring slip from which the clip is formed and the upper looped portions of the clip in particular are sprung together as shown to securely clamp the terminal of the fuse therein. Secure mechanical engagement and good contact is thereby maintained between the clip and the fuse terminals or ferrules mounted therein. A secure and effective mechanical and electrical engagement is thereby maintained between the inner ends of the clip and the fuse terminals or ferrules mounted therein.

From the foregoing it will be apparent that the bails 146 have a double function. They clamp the clip into secure mechanical and good electrical engagement with the terminal of the fuse and by extending around the end of the fuse they serve in addition to prevent accidental displacement of the fuse from the clip irrespective of the clamping effort exerted thereby. Lugs 175 struck up from the opposite side 147 are adapted to limit the swing of the bails in one direction, lugs 175' being struck up to a less degree as shown in Fig. 21 and adapted for cooperation with the bails upon springing the same thereover to prevent accidental swinging of the bails in the opposite direction. The lugs 175' are formed to prevent accidental swinging of the bails 147 and at the same time permit springing of the bails past the same when it is desired to release the fuse. When it is desired to remove the fuse the clips are released by springing the bails past the lugs 175' to the dotted line position 148 shown fragmentarily in Figure 20.

I do not intend to be limited to the precise details shown and described, and I intend that

modification in practicing the various steps such as will be apparent at once to those skilled in the art are contemplated within the scope of the appended claims. Certain phases of the invention are not to be limited to use in connection with fuse structures.

I claim:

1. In a fuse of the character described, a containing casing having a pressure relief opening, a fuse in the container, a liquid arc extinguishing material in the casing, and a removable cap covering said relief opening in the casing, and being sealed thereto by a viscous binder.

2. In a fuse of the class described, a containing casing having a pressure relief opening therein, a metallic ferrule forming a part of the casing about said opening, a fuse in the container, and a releasable metallic plug for the opening, said plug being cemented in place by a viscous binder.

3. In a device of the class described, a fuse casing formed in part of metal, said casing having a pressure relief opening through said metal part, a metal plug for said opening, and a viscous binder sealing said plug in the opening.

4. In a fuse, the combination of a container formed in part of metal, an opening in said metal part, a fuse in the container having a portion thereof adjacent said opening, an arc extinguishing liquid in said casing, and a sheet metal cover for the opening, said sheet metal cover being cemented to the casing about the opening by a relatively non-drying cement and being adapted to be blown clear of the opening by excessive internal pressure.

5. In combination, a closed container, metallic ferrules at the opposite ends of said container, an open ended arcing terminal connected to one of said ferrules, a cooperating open ended arcing terminal, a fuse link connected between said arcing terminals and secured at its opposite ends in the open ends thereof, a clip member, an operating spring clamped between one of said arcing terminals and said clip member, said clip member having an open end, and a conductor secured in the open end of said clip member.

6. In combination, a closed container, a ferrule mounted thereon, said ferrule having a bore providing an internal shoulder, a vent cap adapted for mounting upon said shoulder, said cap having a marginal flange extending along said bore, and being bulged to permit springing of said flange into said bore.

7. A fuse comprising, an open ferrule, a cap ferrule and a cylindrical sleeve cemented into the ferrules, an arc extinguishing liquid therein, said open ferrule having a counterbore at its open end and a disc seated in said counterbore with a nonhardening cement forming a seal and a yielding mechanical binder between the disc and the ferrule.

8. In combination, a container, a metallic

ferrule mounted thereon, a shoulder disposed within the ferrule, an S-shaped supporting member of resilient conducting material disposed on edge with its arms seated upon said shoulder and urged laterally by their inherent resiliency in contact with the peripheral wall of the ferrule, the supporting member being otherwise free from the ferrule, and a terminal member supported by the intermediate portion of the supporting member.

9. In combination, a container, a conductor terminal member secured at one end of the container, an arcing terminal member secured at the other end of the container, a second arcing terminal, a fuse link connecting the two arcing terminals, a second conductor terminal, means securing the second conductor terminal and the second arcing terminal together and forcing them toward each other, a tension spring having one end clamped between said second conductor terminal and the second arcing terminal, means securing the other end of the spring to the first mentioned conductor terminal, and a flexible conductor secured at its ends to the respective conductor terminal members.

10. In combination, a container, a conductor terminal member secured at one end of the container, an arcing terminal secured at the other end of the container, a second arcing terminal, a fuse link connecting the two arcing terminals, a second conductor terminal, means securing the second conductor terminal and the second arcing terminal together and forcing them toward each other, a tension spring having one end clamped between said second terminals, a clamping plate mounted on the first conductor terminal, means for forcing said plate toward the terminal, the other end of the spring being clamped between the plate and its associated terminal, and a flexible conductor secured at its ends to the respective conductor terminals.

11. In combination, a container, a metallic ferrule mounted thereon, an internal shoulder disposed within said ferrule, an S-shaped supporting member of resilient conducting material disposed on edge with its arms seated upon said shoulder and urged laterally by their inherent resiliency into contact with the peripheral wall of the ferrule, a terminal member supported by the intermediate portion of the supporting member, and means pulling on said terminal member to hold the supporting member edgewise in contact with the shoulder.

12. In combination, a container, a metallic ferrule mounted thereon, an S-shaped supporting member of resilient conducting material seated on edge within the ferrule with its arms urged laterally by their inherent resiliency into close contact with the peripheral wall of the ferrule, and a terminal member supported by the intermediate portion of the supporting member, the supporting member being otherwise free from the ferrule.

13. In a fuse of the character described, a container, a metallic ferrule mounted thereon, a shoulder disposed within the ferrule, a fuse connection within the container and a support for one end of said fuse connection, said support comprising a member of conducting material and in the form of an open figure and having an intermediate cross portion for attachment to the fuse connection and resilient arms at its opposite ends seated upon said shoulder, said arms being otherwise free of the ferrule and urged laterally by their inherent resiliency into contact with the peripheral wall of the ferrule.

14. In a fuse of the character described, a container, a metallic ferrule mounted thereon, a shoulder disposed within the ferrule, a fuse connection within the container and a support for one end of said fuse connection, said support comprising a member of conducting material and in the form of an open figure and having an intermediate cross portion for attachment to the fuse connection and resilient arms at its opposite ends seated upon said shoulder, said arms being otherwise free of the ferrule and urged laterally by their inherent resiliency into contact with the peripheral wall of the ferrule, said support being spaced inwardly from the end of the ferrule and the internal diameter of the ferrule outwardly of said support being as large as the external diameter of the support to permit unobstructed removal of the support from the ferrule.

15. In a fuse of the character described, a container, a metallic ferrule mounted thereon, a shoulder disposed within the ferrule, a fuse connection within the container, a support for one end of said fuse connection, said support comprising a member of conducting material and in the form of an open figure and having an intermediate cross portion for attachment to the fuse connection and resilient arms at its opposite ends seated upon said shoulder, said arms being otherwise free of the ferrule and urged laterally by their inherent resiliency into contact with the peripheral wall of the ferrule, said support being spaced inwardly from the end of the ferrule and the internal diameter of the ferrule outwardly of said support being as large as the external diameter of the support to permit unobstructed removal of the support from the ferrule, and spring means associated with the fuse connection and yieldably holding said support upon said shoulder.

16. In a fuse of the character described, a container, a metallic ferrule mounted thereon, a shoulder disposed within the ferrule, a fuse connection within the container, a support for one end of said fuse connection, said support comprising a member of conducting material and in the form of an open figure and having an intermediate cross portion for attachment to the fuse connection

and resilient arms at its opposite ends seated upon said shoulder, said arms being otherwise free of the ferrule and urged laterally by their inherent resiliency into contact with the peripheral wall of the ferrule, said support being spaced inwardly from the end of the ferrule and the internal diameter of the ferrule outwardly of said support being as large as the external diameter of the support to permit unobstructed removal of the support from the ferrule, spring means associated with the fuse connection and yieldably holding said support upon said shoulder, and a vent cap seated within the ferrule outwardly of said support and having a marginal flange extending along and fitting within the ferrule.

17. In combination, a closed container, a ferrule mounted thereon, said ferrule having a bore, a seat within the ferrule, a vent cap adapted for mounting upon said seat, said cap having a marginal flange extending along and adapted to fit within and to extend along said bore and said cap being bulged to permit springing said flange into said bore.

In witness whereof, I hereunto subscribe my name this 4th day of April, 1923.

NICHOLAS J. CONRAD.
